UNITED STATES PATENT OFFICE

121,765

DESIGN FOR A PROTECTIVE MAT FOR BOTTLES, GLASSES, OR THE LIKE

Philip F. Havey, Washington, D. C.

Application December 14, 1939, Serial No. 88,900

Term of patent 7 years

To all whom it may concern:

Be it known that I, Philip F. Havey, a citizen of the United States of America, residing at Washington, in the District of Columbia, have invented a new, original, and ornamental Design for a Protective Mat for Bottles, Glasses, or the like, of which the following is a specification, reference being had to the accompanying drawing, forming a part thereof.

In the drawing:

Figure 1 is a top plan view of the protective mat for bottles, glasses, or the like, in flat, unfolded position; and

Figure 2 is a perspective view of the article, showing my design.

I claim:

The ornamental design for a protective mat for bottles, glasses, or the like, as shown.

PHILIP F. HAVEY.
